DETACHABLE HANDLE AND CONNECTION

Wilbur Jackson, Chatsworth, Ga.

Application September 9, 1946, Serial No. 695,793

2 Claims. (Cl. 287—95)

1

My invention relates to a detachable handle and connection, for rotating the operating shaft of a lifting jack or the like.

An important object of the invention is to provide means for detachably connecting the handle and rotary shaft or element, so that the connection cannot be improperly separated until the connecting element or yoke is swung to approximately right angles to the longitudinal axis of the shaft.

A further object of the invention is to provide means of the above mentioned character which will effect a universal connection between the handle and shaft.

A further object of the invention is to provide a device of the above mentioned character which is simple in construction, strong and durable.

Other objects and advantages of the invention will be apparent during the course of the following description.

In the accompanying drawings forming a part of this application and in which like numerals are employed to designate like parts throughout the same,

Figure 1 is a side elevation of a device embodying my invention,

Figure 2 is a plan view of the same,

Figure 3 is an enlarged longitudinal section taken on line 3—3 of Figure 2, and,

Figure 4 is a longitudinal section taken on line 5—5 of Figure 3.

In the drawings, wherein for the purpose of illustration is shown a preferred embodiment of my invention, the numeral 5 designates a shaft to be rotated. This may be a shaft which is horizontally arranged in use, such as the screw-threaded shaft of the jack shown in my pending application for Jack, Serial #636,778, filed December 22, 1945. This shaft may be held in a fixed horizontal position in use. The shaft 5 is provided at its outer end with a spherically curved end or face 6.

The numeral 7 designates a substantially U-shaped connecting element or yoke, comprising sides 8 and an end 9. The sides 8 are bent inwardly adjacent to the end 9 forming converging portions 10. The end 9 is circularly curved in transverse cross section, as shown in Figure 4 and is straight in longitudinal section, as shown in Figure 3. The end 9 and converging portions 10 form a socket 11. This socket is disposed opposite the spherically curved end 6, when the connecting element 7 extends axially of the shaft 5 and the socket may also be disposed upon the

2

side of the shaft 5, when the connecting element 7 is swung to assume a position at right angles to the longitudinal axis of the shaft 5. The sides 8 are disposed upon opposite faces of the shaft 5, and are pivotally connected therewith by a pin 12, passing through a transverse opening 13, extending diametrically through the shaft 5, near and spaced from the end 6. The opening 13 is spaced from the end 6 a greater distance than the distance from the opening 13 to the side of shaft 5. The curved face or end 6 is concentric with the pivot 12 in a direction axially of the shaft 5.

The numeral 14 designates a preferably rigid rod, constituting the body portion of the handle. This rod may be of a suitable length to reach under an automobile or the like to the jacked position thereunder. At one end, the rod 14 has a radial crank 15, carrying a hand grip 16. At its opposite end, the rod 14 is bent to provide a diagonal axial extension 17, which is bent at its free end to provide a relatively long straight transverse pivotal portion 18. This pivotal portion is circular in cross section so that it can turn upon its longitudinal axis within the socket 11. The entire rod and all portions thereof may be circular in cross section. The relatively long straight pivotal portion 18 has its longitudinal center in alignment with the central longitudinal axis of the rod 14. At its free end, the long straight pivotal portion 18 is bent to provide a diagonal or hooked extension 19, which projects outwardly longitudinally of the axis of the rod 14. This hooked extension extends laterally of the pivotal portion 18, as shown.

In use, when the pivotal portion 18 is held within the socket 11, and the connecting element 7 is extending axially of the shaft 5, the spherically curved end 6 is in close relation to the pivotal portion 18 or substantially contacts therewith. The angular extension or hooked portion 19 now prevents the pivotal portion from being withdrawn from the socket 11, since the pivotal portion 18 will contact with the curved end 6. The rod 14 may be employed to rotate the shaft 6. The connecting element 7 may have limited turning movement upon the pivot 12 and the pivotal portions 18 may turn within the socket 11, thus affording a universal connection between the rod 14 and shaft 5. When it is desired to separate the rod from the shaft 5, the jack being removed from beneath the car, the connecting element or yoke 7 is swung to a position at right angles to the shaft 5, as indicated in Figure 3, and there is then ample clearance between the pivotal por-

tion 18 and the shaft, to permit such pivotal portion being shifted inwardly toward the shaft, so that the lateral extension or hooked portion 19 will clear the end 9, and the pivotal portion may then be removed from within the socket. The parts cannot be separated until the pivotal portion 18 can clear the ends of the curved face 6. It is thus seen that the pivotal portion 18 will be securely retained within the socket until the connecting element or yoke 7 is arranged at substantially right angles to the longitudinal axis of the shaft 5, at which time the parts may be readily separated, as explained.

It is to be understood that the form of my invention herewith shown and described is to be taken as a preferred example of the same, and that various changes in the shape, size, and arrangement of parts may be resorted to without departing from the spirit of my invention or the scope of the subjoined claims.

Having thus described my invention, what I claim is:

1. A detachable handle connection, comprising a shaft having a free end, a substantially U-shaped connecting element including sides and a closed end forming a socket, the sides receiving the free end of the shaft between them and the closed end being spaced from the free end when the U-shaped connecting element extends longitudinally of the shaft, a transverse pin pivotally connecting the sides with the shaft and spaced from the free end of the shaft for a greater distance than it is spaced from that side of the shaft toward which the U-shaped connecting element is swung, and a rod provided with a transverse pivotal portion disposed generally at right angles to the rod and adapted for insertion within the socket to contact with the closed end of the U-shaped connecting element and the free end of the shaft, said transverse pivotal portion having a lateral extension near its free end which projects from the shaft, the arrangement being such that when the substantially U-shaped connecting element is swung to a position generally at right angles to the side of the shaft, the distance be-

45

tween such side and closed end is sufficiently great to permit the separation of the pivotal portion from the socket.

2. A detachable handle connection, comprising 5 a shaft having a curved end, a substantially U-shaped connecting element including sides and a closed end forming a socket, the sides receiving the curved end of the shaft between them and the closed end being spaced from the curved end 10 when the U-shaped connecting element extends longitudinally of the shaft, a transverse pin pivotally connecting the sides with the shaft and spaced from the curved end of the shaft for a greater distance than it is spaced from that side of the shaft toward which the U-shaped connecting element is swung, the transverse pin being substantially concentric with the curved end, and a rod provided with a transverse pivotal portion disposed generally at right angles to the rod and adapted for insertion within the socket 15 to contact with the closed end of the U-shaped connecting element and the curved end of the shaft, said transverse pivotal portion having a lateral extension near its free end which projects from the shaft, the arrangement being such that when the substantially U-shaped connecting element is swung to a position generally at right angles to the side of the shaft, the distance between such side and the closed end is sufficiently great to permit the separation of the pivotal portion from the socket.
